UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL COMPOSING-MACHINE.

1,086,620.

Specification of Letters Patent.

Patented Feb. 10, 1914.

Original application filed January 24, 1912, Serial No. 673,092. Divided and this application filed March 31, 1913. Serial No. 757,859.

To all whom it may concern:

Be it known that I, JOHN R. ROGERS, a citizen of the United States, residing at Brooklyn, in the county of Kings and State 5 of New York, have invented certain new and useful Improvements in Typographical Composing-Machines, of which the following is a specification, reference being had therein to the accompanying drawing, and 10 being a division of an application filed by me on the 24th day of January, 1912, Serial No. 673,092.

My invention relates to typographical composing machines, such as linotype machines of the general organization represented in Letters Patent of the United States, 15 No. 436,532, to O. Mergenthaler, wherein circulating matrices are released from a magazine in the order in which their characters are to appear in print and then assembled in line, together with expanding spacers, the composed line transferred to the face of a mold, the mold filled with molten metal to form a slug or linotype against the matrices which produce the type characters thereon, and the matrices thereafter elevated and returned through a distributing mechanism to the magazine or magazines from which they started. This elevation of the matrices to the distributing mechanism is generally effected by a device known as the "second" elevator, which ordinarily comprises a grooved V-shaped rail or bar to engage in correspondingly shaped notches in the matrices. When, therefore, plural character type or matrices are used, and when they are assembled at different levels, it is necessary to restore them to the same level before they can be engaged by the said bar. 40 However, in my pending application for Letters Patent Serial No. 559,784, filed May 5th, 1910, I have departed from this form of elevator, and have shown it of such construction that the matrices may be delivered thereto at different levels and thereafter permitted to assume the same level therein. In the particular form under discussion, the elevator is provided with inwardly projecting flanges or ledges to engage the ears of 45 the matrices and thereby to support them during their movement to the distributor. In practice, and due to the previous withdrawal of the spacers from the line, it occurs that the matrices are ordinarily not de-

livered to the elevator in compact relation 55 to each other, but are held loosely therein and simply by the engagement of their ears with the ledges or flanges. This occasionally results in the lateral turning or twisting of the matrices to a sufficient extent to 60 disengage their ears from the ledges and thus to permit them to drop therefrom.

It is the object of my present invention to overcome these objections, and to that end I propose to provide the elevator with auxiliary means which will allow the matrices to be introduced therein at different levels, but which will engage them when restored to the same level and prevent such twisting or turning. 70

It is a further object of my invention to adapt these auxiliary means to assist and insure the leveling of the matrices within the elevator.

While in the accompanying drawings I 75 have shown my improvements in preferred form and by way of example, and as applied to a linotype machine, it is obvious that many changes and variations may be made therein, and in their mode of application, 80 without departure from the scope of the invention; and generally speaking, I desire it to be understood that I do not limit myself to any specific form or embodiment, except in so far as such limitations are specified in 85 the claims.

Referring to the drawings: Figure 1 is a longitudinal vertical section showing the second elevator in receiving position and having my invention applied thereto; Fig. 90 2 is a transverse vertical section taken on the line 2—2 of Fig. 1; and Fig. 3 is a horizontal section taken on the line 3—3 of Fig. 1.

Referring to Fig. 1, the assembled line, 95 consisting of the matrices X and spacers Y, is shown in the process of transfer from the first elevator C to the upper transfer channel E wherein the spacers are free from the matrices, this being accomplished in the ordinary way by the engagement of the spacer ears in the usual grooves E¹, along which they travel and are restored to their magazine Y¹. Simultaneously, the matrices X are moved into the second elevator F, 100 which is of substantially the same construction as that disclosed in my previously mentioned application, being box-like in form 105

and provided at its bottom with two inwardly-projecting flanges F^1 designed to engage under and support the upper ears X^1 of the matrices X . As in my said application, this form of elevator permits the introduction of the matrices thereto at different levels and allows them to assume a common level therein. It will be noted that the elevator C is provided with two sets of supporting ledges C^1 and C^2 to maintain the matrices at different levels therein, the matrices being formed in their upper ears with notches X^3 which engage the upper ledges C^2 when presented at the higher level. It will also be noted that the upper transfer channel E is provided with short ledges E^2 (only one being shown) to register with the upper ledges C^2 of the first elevator C so as to guide the matrices supported thereby to the second elevator F , the matrices supported by the lower ledges C^1 being guided by the bottom ledges E^3 of the transfer channel.

Coming now to my improvement, I employ a bar F^2 connected to the second elevator F and movable relatively thereto, the bar being preferably V-shaped in cross section to engage with the corresponding V-shaped notches X^2 in the matrices X . The bar F^2 is supported by the cross pieces or yokes F^3 and is mounted in a recess in the upper portion of the elevator F so as to be capable of a limited vertical movement with respect thereto. The cross pieces or yokes F^3 project beyond the elevator and are provided at their outer ends with downwardly extending pins F^4 located in position to engage the upper edges of the transfer channel E . When the elevator F descends to its receiving position within the channel E , the pins F^4 contact with the edges of the channel in such manner as to arrest the bar F^2 and to permit a slight further downward movement of the elevator proper. This leaves the bar in its uppermost relative position in the elevator and out of the way of the advancing matrices X , which may be then introduced into the elevator at different levels. After the matrices are located within the elevator and it starts upward, it will first move with reference to the bar F^2 until the latter is in its lowermost relative position therein, at which time its further upward movement carries the pins F^4 out of contact with the edges of the channel E . This downward movement of the bar F^2 , due to gravity or otherwise, within and with reference to the elevator F , and by reason of its engagement with the matrices X therein, will assist in bringing all of them to their lower positions with their lugs X^1 resting upon the flanges F^1 . In addition, the subsequent engagement of the V-shaped bar in the V-shaped notches in the matrices prevents their lateral turning or

twisting and the consequent disengagement of their lugs X^1 from the flanges F^1 .

As previously stated, I have shown my improvements in preferred form and by way of example but obviously many changes and variations therein and in their mode of application will suggest themselves to those skilled in the art and still be comprised within their spirit.

Having thus described my invention, its construction and mode of operation, what I claim and desire to secure by Letters Patent of the United States is, as follows:

1. In a typographical machine, the combination of the first elevator provided with means for supporting the type or matrices at different levels, and the second elevator formed to receive the type or matrices therefrom while standing at such levels and provided with further means to bring them to a common level therein. 85

2. In a typographical machine, the combination of the first elevator provided with means for supporting the type or matrices at different levels, and the second elevator formed to receive the type or matrices therefrom while standing at such different levels and then to permit them to assume the same level therein, together with auxiliary means to assist the leveling of the type or matrices. 90

3. In a typographical composing machine comprising type or matrices having projecting ears, the movable second or distributing elevator provided with means to support the type or matrices by their ears and carrying auxiliary means to prevent their lateral turning. 100

4. In a typographical composing machine comprising type or matrices having projecting ears, the movable second or distributing elevator provided with flanges to support the type or matrices by their ears and carrying auxiliary means to prevent the disengagement of the ears from the flanges. 105

5. In a typographical composing machine comprising type or matrices having projecting ears and notches, the movable second or distributing elevator provided with means to support the type or matrices by their ears and carrying auxiliary means to engage in said notches to prevent the matrices from turning laterally. 115

6. In a typographical composing machine comprising type or matrices having projecting ears and V-shaped notches, the movable second or distributing elevator provided with means to support the type or matrices by their ears and carrying an auxiliary V-shaped bar to engage in the matrix notches to prevent them from turning. 120

7. In a typographical machine, the combination of the first elevator provided with means for supporting the type or matrices at different levels, and the second elevator adapted to receive the type or matrices there- 125

from while standing at such different levels and provided with means movable relatively thereto to permit the reception of the type or matrices at different levels and then to engage them.

8. In a typographical machine comprising type or matrices formed with notches, the combination of the first elevator provided with means for supporting the type
10 or matrices at different levels, and the second elevator adapted to receive the type or matrices therefrom while standing at such levels and provided with means movable relatively thereto to permit the reception
15 of the type or matrices at different levels and then to engage their notches.

9. In a typographical composing machine comprising matrices formed with V-shaped notches, the second or distributing elevator provided with means to receive the matrices 20 at different levels and with a V-shaped bar movable relatively to the elevator to permit the reception of the matrices at different levels and then to engage in the matrix notches.

In testimony whereof I have affixed my signature in presence of two witnesses.

JOHN R. ROGERS.
